WOVEN WICK FOR OIL BURNERS AND THE
LIKEGustav Walters, Middletown, Conn., assignor to
The Russell Manufacturing Company, Middle-
town, Conn., a corporation of Connecticut

Application June 1, 1937, Serial No. 145,652

4 Claims. (Cl. 139—388)

This invention relates to an improvement in wicks and more particularly to woven wicks for oil stoves, etc. Woven wicks as heretofore produced have been generally characterized by two opposite face plies tied together by the usual longitudinal binder-strands extending between the said plies and have possessed many objections among which may be mentioned relatively low capillarity, variation from standard thicknesses, 10 possession of longitudinal rib-like bulges at diametrically-opposite points thereon, unevenness in their edges, etc., etc. The present invention contemplates a woven wick of such character as will obviate many of the defects above mentioned.

One of the objects of the present invention is to provide a woven wick which will maintain a burning-edge of superior uniformity when in use.

20 A further object is to provide a woven wick having superior capacity for conducting liquid fuel to its burning-edge.

Another object of the present invention is to provide a woven wick characterized by a superior 25 degree of uniformity in thickness and resiliency.

A still further object is to provide a superior woven wick characterized by relative freedom from objectionable longitudinal rib-like bulges common in prior types of tubular woven wicks.

30 With the above and other objects in view, as will appear to those skilled in the art from the present disclosure, this invention includes all features in the said disclosure which are novel over the prior art.

35 In the accompanying drawing:

Fig. 1 is a view in side elevation of a seamless tubular woven wick embodying the present invention and shown as mounted in a perforated carrier;

40 Fig. 2 is a perspective view of the wick prior to its introduction into a carrier;

Fig. 3 is a schematic view in longitudinal section illustrating one weave suitable for carrying out the present invention; and

45 Fig. 4 is a similar view of still another weave suitable for use in wicks of the present invention.

The particular woven wick 10 herein chosen for the illustration of one embodiment of the 50 present invention is of seamless tubular form as shown in Fig. 2 and may be inserted into a tubular perforated metal carrier 11 in accordance with usual practice.

The particular weave illustrated in Fig. 3 includes a plurality of sets or groups of warp

strands which in the present instance comprise six strands, each respectively designated 12, 13, 14, 15, 16 and 17. The said warp strands pass through the fabric on a long gentle slope and alternately pass over weft strands or picks 18 5 in one face of the fabric and over weft strands or picks 19 in the opposite face of the fabric.

By way of example the warp strand 12 may be considered and it will be noted by reference to Fig. 3 that after passing over the first of 10 the upper weft picks 18^a the said strand misses engagement with a total of six weft picks 18 and 19 before appearing on the opposite face of the fabric for extension around the weft pick 19^a. The warp strand 12 then extends diagonally through the fabric on a long gentle slope to the opposite face of the fabric and again misses six weft picks before looping over the weft pick 18^b. The remaining warp strands 13, 14, 15, 16 and 17 are all staggered with respect to the 20 strand 12 and each other in the order named and each thereof similarly misses six picks between its appearance on the respective opposite faces of the fabric, as clearly shown in Fig. 3.

It will be understood, of course, that other 25 sets of warp strands corresponding to the warp strands 12 to 17 inclusive exist in the fabric in the background of the strands shown in Fig. 3. By way of example, the next strand back of the warp strand 17 would be a strand corresponding 30 in position and inclination to the warp strand 12.

The weave illustrated in Fig. 3 may be aptly characterized as an interwoven twill inasmuch as each of the warp strands extends through 35 the fabric from one side to the other thereof and does not require the use of binder-strands to tie the two sets of weft strands 18 and 19 together.

The particular weave illustrated in Fig. 4 includes a plurality of sets or groups of warp strands which comprise six strands each respectively designated 20, 21, 22, 23, 24 and 25 arranged from the foreground to the background in the order named. In the upper face of the fabric (as viewed in the drawing) is a series of weft strands 45 or picks 26 and in the opposite face is a corresponding series of weft strands or picks 27. The said weft strands or picks 26 in one face are tied to the weft strands or picks 27 in the other face solely by the warp strands 20 to 25 50 inclusive before referred to. The said warp strands all extend on a long gentle slope from one face of the fabric to the other, and like the weave shown in Fig. 3 each of the said warp strands misses six weft picks between its appear- 55

ance upon the respective opposite faces of the fabric.

It may be explained in this connection that in the weave of Fig. 4 the next strand in the background beyond the strand 25 would be another strand corresponding in position to the position of the strand 10 and constituting the first strand of another group of similar warp strands.

10 Both of the weaves illustrated and above described are characterized by high capacity for conducting oil to the burning-edge of the wick, which in each of the figures of the drawing is designated by the reference character 28, and as 15 the said burning-edge chars in use, the said edge will remain substantially even owing largely to the fact that all of the longitudinal strands are of the same length, which has not been the case in prior types of tubular woven wicks which have 20 employed binder-strands which have very materially exceeded the length of the ordinary warp strands in the various plies so that as the material of such prior wick burns back, the longer binder-strands are free to extend themselves beyond 25 the nominal edge of the wick, thus producing an uneven flame.

Furthermore, by means of the present invention the wick may be woven to predetermined thickness much more accurately than has been 30 possible with prior types of weaves employed in seamless tubular woven wicks, since in most of the prior types of seamless tubular woven wicks, the tension applied to the binder-strands during the weaving operation very materially varies the 35 thickness of the fabric. Also in the prior tubular woven wicks, the presence of the great multiplicity of binder-strands not only deprived the wick of desirable resiliency but also so closely filled the interstices between the various warp 40 strands as materially retarded the capacity of the wick to conduct oil or other liquid fuel to its burning-edge.

In weaving seamless tubular woven wicks of many of the types prior to the present invention, a very marked deformation took place at 45 diametrically opposite points on the wick where the weft or filling picks reversed. The defect just mentioned has been so minimized when wicks are woven in seamless tubular form by means of the present invention that it may be regarded as 50 negligible.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

60 I claim:

1. A woven wick substantially free of binder strands and consisting substantially of: a set of

weft picks located adjacent one surface of the wick; another set of weft picks located adjacent the other surface of the wick; and a plurality of warp strands, all of which warp strands extend diagonally back and forth through the fabric, and each of which warp strands alternately passes over a weft pick of one set of weft picks and then over another pick of the other set of weft picks, and passes between a plurality of the intervening weft picks of both sets of weft picks 10 between its leaving and returning to a given set of weft picks.

2. A woven wick substantially free of binder strands and consisting substantially of: a set of weft picks located adjacent one surface of the 15 wick; another set of weft picks located adjacent the other surface of the wick; and a plurality of groups of more than three warp strands, all of which warp strands extend diagonally back and forth through the fabric, and each of which warp strands alternately passes over a weft pick 20 of one set of weft picks and then over another pick of the other set of weft picks, and passes between a plurality of the intervening weft picks of both sets of weft picks between its leaving and 25 returning to a given set of weft picks, and the individual strands composing a given group of warp strands being in longitudinally-staggered relationship with respect to other warp strands of the same group.

3. A woven wick substantially free of binder strands and consisting substantially of: two sets only of weft picks, one set located adjacent one surface and the other set located adjacent the other surface of the wick; and a plurality of 30 groups of six warp strands, all of which warp strands extend diagonally back and forth through the fabric, and each of which warp strands alternately passes over a weft pick of one set of weft picks and then over another pick of the other set of weft picks, and passes between a plurality of the intervening weft picks of both sets of weft picks between its leaving and returning to a given set of weft picks.

4. A seamless tubular woven wick substantially 45 free of binder strands and consisting substantially of: two sets only of weft picks, one set located adjacent one surface and the other set located adjacent the other surface of the wick; and a plurality of groups of six warp strands, all of which warp strands extend diagonally back and forth through the fabric, and each of which warp strands alternately passes over a weft pick 50 of one set of weft picks and then over another weft pick of the other set of weft picks, and passes between a plurality of the intervening weft picks of both sets of weft picks between its leaving and returning to a given set of weft picks, and the individual strands composing a given group of warp strands being in longitudinally-staggered relationship with respect to other warp strands of the same group.

GUSTAV WALTERS.
